LELAND H. HILL, OF SWISSVALE, AND WALTER M. DANN, OF WILKINSBURG, PENNSYLVANIA, ASSIGNORS TO WESTINGHOUSE ELECTRIC & MANUFACTURING COMPANY, A CORPORATION OF PENNSYLVANIA.

SYSTEM OF DEOXIDIZATION.

Application filed September 10, 1924, Serial No. 736,829. Renewed July 12, 1926.

Our invention relates to the production of an inert atmosphere in electrical devices and particularly to the deoxidation of the gas initially confined therein.

5 One object of our invention is to provide an electrical translating device with means for deoxidizing or dehydrating the gases originally confined therein.

Another object of our invention is to provide 10 an electrical translating device that is equipped with a chamber for deoxidizing or dehydrating the incoming gas that shall also be provided with means for insuring the circulation of the air or gases already confined 15 in the translating device into contact with the dehydrating or deoxidizing medium.

It is a further object of our invention to provide 20 an electrical translating device having means for dehydrating or deoxidizing incoming gases with means that shall insure the circulation of air or gases initially contained in such device into contact with the dehydrating or deoxidizing medium by employing convection currents created by the 25 temperature of the translating device.

It is now customary practice to provide 30 electrical translating devices, such as oil immersed circuit interrupters or transformers, with an atmosphere of dehydrated or deoxidized gas above the level of the insulating oil in order to avoid the dangers of explosions 35 incidental to the formation of explosive mixtures of hydrocarbon gases and air within such devices. In order to suitably modify the air entering such translating devices during 40 the process of "breathing", it has been found practicable to insert a container filled with suitable dehydrating or deoxidizing material between the external atmosphere and the atmosphere 45 above the insulating fluid in the translating device. Such devices, however, are capable of dehydrating and deoxidizing the atmosphere initially confined in such translating devices only by diffusion with the treated air drawn in during "inbreathing". Accordingly, we propose to facilitate deoxidization and dehydration of the initially confined gas by causing it to circulate into contact with the deoxidizing or dehydrating material without having to discharge it into the surrounding atmosphere.

In the accompanying drawings, the single figure is a view, partially in elevation and partially in section, of an electrical translating device equipped with our invention. 55

Our invention comprises, in general, an electrical translating device 1, such as a transformer, in which the operating windings 2 are surrounded by an insulating and cooling fluid 3, such as oil, and having a chamber 4 attached to the casing of the translating device 1 that, in turn, communicates, through an orifice 5, located in the lower part of the translating device 1, with a conduit or pipe 6 that extends upwardly above the level of the insulating oil 3. 60

The electrical translating device 1 is provided with a cover member 7 through which suitable insulating bushings 8 extend for containing the conductors 9 connected to the windings 2. The cover member 7 is secured by suitable clamping bolts 11 to the tank portion 12 of the translating device. 70

An orifice 13 is provided in the tank portion 12 near its upper edge and above the level 75 of the insulating oil 3. The orifices 5 and 13 are preferably in alignment with each other. The pipe 6 extends upwardly beyond the upper edge of the orifice 13.

The chamber 4 is detachably secured to the tank 80 12 by means of bolts 14 in such manner that it covers the orifices 5 and 13. Within the chamber 4 is placed a pair of parallel-extending screens 15 that divide the chamber into small compartments. The compartment 85 bounded by the screens 15 is filled with the dehydrating and deoxidizing material 16. As the particular composition of the dehydrating and deoxidizing compound forms no part of the present invention, a discussion of such 90 material is omitted from this application. On one side of the deoxidizing material 16 is a compartment 17 that communicates through a regulating valve 18 with the atmosphere. On the other side of the deoxidizing material 95 16 is a compartment 19 that extends vertically from the orifice 13 to the orifice 5.

The latter compartment is relatively wide and thin in order that a maximum area of surface of the deoxidizing material 16 is presented to gas traversing the compartment. 100

Upon the assembling of an electrical trans-

lating device 1, the tank 12 is filled with the insulating fluid 3 either before or after the cover member 7 is clamped thereto. In either event, a quantity of air is trapped between the cover member 7 and the level of the insulating fluid 3, which air has neither been deoxidized nor dehydrated and is therefore likely to combine with hydrocarbon vapors to form an explosive mixture. Changes in the volume of the gas within the translating device 1 occur by reason of changes in the level of the insulating oil, caused by changes in its temperature. Fluctuations in temperature cause variations in pressure in the tank and corresponding escape of gas or breathing in of air occurs when the pressure reaches predetermined maximum or minimum values. The original atmosphere confined in the translating device 1 eventually becomes an inert gas by diffusion with the purified gases passing through the chamber 4.

In order to facilitate the deoxidation and dehydrating of the air or gas originally enclosed in the translating device 1, we have provided the orifice 5 at the lower portion of the tank 12 and the pipe 6. Under working conditions of the windings 2, a certain amount of heat is transmitted to the insulating oil 3, some of which is, in turn, transmitted to the walls of the pipe 6, thereby causing convection currents to be set up through the orifice 13, the compartment 19, the orifice 5 and the pipe 6 in the direction shown by the arrows in the drawing, that direction being the same as the order of the parts just enumerated.

Since the outlet of the pipe 6 is considerably above the upper wall of the orifice 13, the gas discharged therefrom crowds the cooler gas above the level of the fluid 3 through the orifice 13 and into the compartment 19. The gas above the fluid 3 is cooled by the continuous radiation of heat through the cover member 7.

This gas being relatively cool, tends to settle downwardly through the compartment 19 where it engages the surface of the deoxidizing compound 16. It is obvious that this convection current continues indefinitely and serves to continuously purify the gas contained in the translating device 1.

The pressure required to cause a circulation of the gas through the compartment 19 and the pipe 6 is very low as compared with that required to cause "inbreathing" or "out-breathing" through the regulating valve 18 and accordingly, the function of the regulating valve is in no way interfered with by the provision of the internal purifying passage.

Any tendency toward the creation of a vacuous condition by reason of the loss of oxygen is cared for by new gas breathed into the translating device.

Accordingly, we have provided a means for

purifying the gas initially confined in the electrical translating device 1 by causing such gas to circulate across the face of the deoxidizing material through which all incoming gas to the translating device 1 must pass.

We do not wish to be restricted to the specific arrangement of parts herein set forth, as various modifications thereof may be effected without departing from the spirit and scope of our invention. We desire, therefore, that only such limitations shall be imposed as are indicated in the appended claims.

We claim as our invention:

1. In combination, a container partially filled with gas and having an orifice communicating with the atmosphere, means co-operating with the container for treating any air entering the container from the surrounding medium, and automatic means for circulating the contained gas into engagement with the treating means.

2. In combination, a container partially filled with gas and having an orifice communicating with the atmosphere, means co-operating with the container for rendering inert any air entering the container from the surrounding medium, and means for circulating the contained gas into engagement with said means by reason of the difference in temperature between the contained gas and said means.

3. In combination, a container partially filled with gas, a chamber associated with the container, and means for causing the gas in the container to circulate through said chamber without physical change thereof.

4. In combination, a container partially filled with gas, a chamber associated with the container, and means for causing the gas in the container to circulate through said chamber without physical change by reason of the difference between the temperatures of the contained gas and of said chamber.

5. In combination, an electrical device partially filled with gas, a chamber associated with the electrical device, and means for causing the gas in the electrical device to circulate through said chamber without physical change thereof.

6. In combination, an electrical device partially filled with gas, a chamber associated with the electrical device, and means for causing the gas in the electrical device to circulate through said chamber without physical change by reason of the difference between the temperatures of the gas contained in the electrical device and of said chamber.

7. In combination, a container partially filled with gas and having a plurality of orifices located at different levels, a chamber associated with the container and communicating with the orifices and means attached

to the container adjacent to the lower orifice and in communication with the chamber for conveying gas from the bottom of said chamber to a point in the container above the upper orifice.

8. In combination, a container partially filled with gas and having a plurality of orifices located at different levels, a chamber associated with the container and communicating with the orifices, and a conduit attached to the container adjacent to the lower orifice and in communication with said chamber for conveying gas from the bottom of said chamber to a point in the container above the upper orifice.

9. In combination, a container partially filled with gas and having a plurality of orifices located at different levels, a chamber associated with the container and communicating with the orifices, and a conduit attached to the container adjacent to the lower orifice and in communication with said chamber for conveying gas from the bottom of said chamber to a point in the container above the upper orifice, the conduit being subjected to the temperature of the contents of the container throughout its entire length.

10. In combination, a container partially filled with gas and having a plurality of orifices located at different levels, a chamber associated with the container and communicating with the orifices, and a conduit attached to the container adjacent to the lower orifice and in communication with said chamber for conveying gas from the bottom of said chamber to a point in the container above the upper orifice, the conduit being subjected to the temperature of the contents of the container throughout its entire length.

11. Protective device for liquid insulated electric apparatus comprising means for causing a permanent circulation of the air in said apparatus above the liquid level and means for absorbing the oxygen in the air.

In testimony whereof, we have hereunto subscribed our names this 4th day of September, 1924.

LELAND H. HILL.
WALTER M. DANN.
